UNITED STATES PATENT OFFICE

MICHAEL H. FLYNN, OF HARTFORD, CONNECTICUT, ASSIGNOR TO ROYAL TYPEWRITER COMPANY, INC., OF NEW YORK, N. Y., A CORPORATION OF NEW YORK.

ASSEMBLING-FRAME FOR MACHINES.

1,220,507.

Specification of Letters Patent. Patented Mar. 27, 1917.

Application filed May 20, 1915. Serial No. 29,316.

To all whom it may concern:

Be it known that I, MICHAEL H. FLYNN, a citizen of the United States of America, residing in Hartford, in the county of Hartford and State of Connecticut, have invented a certain new and useful Assembling-Frame for Machines, of which the following is a specification.

In assembling typewriting and other machines composed of a number of parts considerable labor is involved in setting and holding such machines in the various positions necessary for such operations. The object of this invention is to provide a holding frame to which the machine to be assembled may be fastened and which is adapted to be set and retained in various positions, thus permitting free access to all parts of the machines and saving the labor and time of the assembling operator in lifting the machines and holding them in different positions.

In the preferred form of this invention, the machine holding frame is axially held in a supporting frame on a horizontal line preferably passing through the general center of gravity of the machine held by the frame, suitable stops being provided for determining the principal positions requisite to hold the machine during the assemblage of the various parts of the same. To further facilitate this work the supporting frame may be made to move about a vertical axis also preferably arranged to pass through the center of gravity of the machine and in the same vertical plane with the horizontal axis of the swinging frame, or approximately so.

The device in detail will now be described by reference to the accompanying drawings, in which:

Figure 1 is a perspective view showing the swinging machine holding frame in horizontal position:

Fig. 2, a similar view showing said frame in a vertical position:

Fig. 3, a sectional view of the base of the device on the line 3, 3, of Fig. 1:

Fig. 4, a similar view showing the machine frame holding spring in a different position:

Fig. 5, a detached section of the frames on line 5, 5, Fig. 1:

Fig. 6, a section on line 6, 6, Fig. 2:

Fig. 7, a detached view of one of the rock-

ing connections of the swinging and supporting frame:

Fig. 8, illustrates a modification showing the machine holding bed piece in horizontal position: and

Fig. 9, a view at right angles to Fig. 8 showing the bed piece in a vertical position.

The bed piece to which the machine is fastened is rectangular, consisting of sides 10, 10, and a back 11. The sides have 65 formed in their inner edges recesses 12, arranged to correspond with the location of the supporting feet of the machine to be assembled, which machine is secured to the parts 10 by screw bolts 13; said recesses being cut away at their forward ends 14 to afford a free entrance for the heads of the bolts after they are applied to the machine, thus providing for the ready application of the machine to, and its removal from, the 70 bed piece with the bolts loosely screwed in position. This provides for quickly setting the machine on the bed piece and moving it from one assembling frame to another, or the bed piece 10, 11 may be retained on the 80 machine and moved with it to other supporting frames, constructed as hereinafter described. The dotted lines 15 of the drawings represent the main frame of a Royal typewriter, showing the bolts 13 screwed in 85 the holes for the feet of the machine. The parts of the frame adjacent the recesses 12 that are clamped between one side of the heads of bolts 13 and the bottom of a machine frame are shown thinner than other 90 parts of the side pieces 10, see Fig. 6.

The side pieces 10 are provided with lateral upwardly extending arms 16, whose upper ends have lateral trunnions or studs 17, which constitute the swinging axis of 95 the bed piece 10, 11, and are so located as to approximately pass through the center of gravity of the machine secured to the bed piece while being assembled. The studs 17 seat in slotted open bearings 18 formed in 100 the tops of the side bars 19 of the bed piece supporting frame, said side bars being connected together by a bottom bar 20. At the tops of the arms 16 are extensions 21 so formed and arranged as to contact with the 105 sides of the side bars 19 (as shown at Fig. 7) and thus act as stops to determine the vertical position of the bed piece 10, 11, and the machine held thereon, for free access to the under side of the machine, as shown at 110

Fig. 2. The arms 16 may be integral with the side pieces 10, or secured thereto by screws 22, as shown.

The rear edges of the upright bars 19 of the supporting frames are provided with stops 23, against which the back edges of the arms 16 rest when the bed piece 10, 11 is set in horizontal position. These stops 23 may be conveniently formed by notching 10 the bars 19, as at 24, and bending the notched pieces inwardly, as shown at Fig. 5.

The bottom bar 20 of the supporting frame is secured by screws 26, 26 to a turn table 27 provided with a circular boss or lug 15 28 fitting in a central hole in the circular base 29, which by means of screws may be conveniently secured to a bench. By this arrangement the bed piece and machine, in whatever position they may be set, may be 20 rotated on a vertical axis and free access had to all parts of the machine. This vertical axis is practically in the same plane with the horizontal axis of the bed piece and substantially passes through the center of 25 gravity of the machine.

A spring 30 adjustably clamped between the central part of bar 20 and turn table 27 has its outer end 31 formed to engage with 30 a notch 32 in the bar 11, whereby the bed piece and machine are held in a vertical position, as shown in Figs. 2 and 3, thus leaving both hands of the operator free to work on the machine while attending to the heavier adjustments thereof.

Different styles of machines may be assembled on this device. For larger machines, or those having a deeper frame, special bed pieces will be used, their arms 35 16 being longer than those shown, and in such use of the device the spring 30 will be set and held in outer position to engage the bar 11, as shown at Fig. 4, the sharp bend 40 in its base then being at the outer edge of the bar 20 whereas in the other case it is 45 against the inner edge of the bar.

In the modification shown in Figs. 8 and 9, the turn table part is omitted and the supporting frame 19, 20 is shown secured directly to a bench. In other respects all of 50 the parts may be like the corresponding parts of the device previously described and are similarly designated. The bed piece may in this case be provided with a counter-weight 33 to hold the machine in different 55 angular positions.

As the machine which is being assembled and adjusted is supported on an axis passing through its center of gravity it will rest in whatever position it is set and the labor 60 of lifting the machine for such manipulations is avoided and both hands of the operator are free for useful work.

I claim:

1. An assembling frame for machines, 65 comprising a bed piece adapted to hold a

machine to be assembled, a supporting frame having vertical arms in which the bed piece is held and adapted to rock on a horizontal axis having also a horizontal bottom bar and a base for the supporting frame to 70 which said bottom bar is pivoted on which it is free to turn on a vertical axis.

2. An assembling frame for machines, comprising a bed piece adapted to hold a machine to be assembled and having vertical 75 arms provided with lateral trunnions, a supporting frame having bearings in which the trunnions seat, stops for determining the two extreme positions of the bed piece, a base on which the supporting frame is carried and a rotatable connection between the supporting frame and base the vertical axis of which is substantially in plane with the 80 rocking axis of the bed piece.

3. An assembling frame for machines, 85 comprising a bed piece adapted to hold a machine to be assembled and having lateral trunnions, a supporting frame having bearings in which the trunnions seat, stops for determining the two extreme positions of 90 the bed piece and a spring at the lower part of the supporting frame adapted to hold the bed piece in upper position.

4. An assembling frame for machines, comprising a bed piece adapted to hold a 95 machine to be assembled and having lateral trunnions, a supporting frame having open bearings in which the trunnions of bed pieces of various sizes seat, stops for determining the two extreme positions of the bed piece and an adjustable spring at the lower part 100 of the supporting frame adapted to be set to hold the different size bed pieces in vertical positions.

5. An assembling frame for machines, 105 comprising a bed piece adapted to hold a machine to be assembled and having vertical arms provided with lateral trunnions, a supporting frame having bearings in which the trunnions seat, stops for determining the two extreme positions of the bed piece, a base and a turn table secured to the supporting frame resting on the base and having a bearing with a vertical axis of rotation on the base. 110

6. An assembling frame for machines, comprising a bed piece adapted to hold a machine to be assembled and having lateral trunnions, a supporting frame having bearings in which the trunnions seat, stops for 120 determining the two extreme positions of the bed piece, a base, a turn table secured to the supporting frame resting on the base and having a bearing with a vertical axis of rotation on the base and a spring clamped 125 between the supporting frame and base adapted to hold the bed piece in upper position.

7. An assembling frame for machines, comprising a bed piece adapted to hold a 130

machine to be assembled, a supporting frame in which the bed piece is held and adapted to rock on a horizontal axis, a base for the supporting frame on which it is free to turn 5 on a vertical axis and a spring carried by the supporting frame and adapted to hold the bed piece in upper set position.

In testimony whereof, I have hereunto subscribed my name.

MICHAEL H. FLYNN.
